UNITED STATES PATENT OFFICE.

WILLIAM N. PELOUZE, OF CHICAGO, ILLINOIS.

DESIGN FOR A SCALE-DIAL.

SPECIFICATION forming part of Design No. 30,399, dated March 28, 1899.

Application filed February 28, 1898. Serial No. 672,098. Term of patent 14 years.

To all whom it may concern:

Be it known that I, WILLIAM N. PELOUZE, a citizen of the United States, residing at Chicago, in the county of Cook and State of Illinois, have invented and produced a certain new and original Design for Scale-Dials, of which the following, in connection with the accompanying drawings, is a full, clear, and exact specification.

10 In the said drawings, Figure 1 is a face view of a scale-dial embodying my design; and Fig. 2 is a transverse section thereof, looking downwardly.

The leading features of my design consist 15 of the scale-dial having the thin flat face A and the border B, rounding outwardly from said face and thence flaring rearwardly to a plane in the rear of said face, the inner or reverse side of said dial presenting the appearance of a circular flat plate surrounded 20 by the concavity b, rounding off into a concaved flaring rim extending considerably to the rear of the flat plate.

The face A is slightly depressed below the outer edge or apex of the border B, which border is rounded outwardly and forwardly away from the plate A and then carried rearwardly, as shown in Fig. 2, so that its diameter continually increases from its apex or bend, and as a consequence the broad rearwardly-curving or beveled border surrounding the plate A is produced when viewed as in Fig. 1.

The reverse side of the dial A is also flat and of substantially the same thickness as 35 the flaring border B, which where it joins the dial on the reverse side forms a bend or concavity b parallel with the outer or convex side of the border B.

I claim—

40 The design for a scale-dial substantially as herein shown and described.

WM. N. PELOUZE.
